UNITED STATES PATENT OFFICE

2,439,639

ENVELOPE AND PACKAGE OPENER

James O. Tilly, Tulsa, Okla.

Application October 9, 1944, Serial No. 557,905

1 Claim. (Cl. 30—294)

1

My invention relates to an improvement in envelope and package opening devices and an advertising novelty. The object of the device is to provide an envelope and package opener having a guide, a knife and a handle portion so assembled that the guide will guide the knife for envelope opening and paper cutting. A further object is to provide a device of the kind mentioned in which the knife is held in an advantageous position for cutting purposes and yet the knife is shielded so that there is no danger of one cutting himself while using the device and also preventing accidental cutting when the device is not being used. A still further object is to provide a device of the kind mentioned in which the handle portion becomes a protective element for the knife, also the handle element may be made as a replica of some object or merchandise to be employed as an advertising medium for the merchandise or services rendered by the advertiser. A still further object is to provide a device of the kind mentioned that is simple, easy and cheap to manufacture and sell as well as being attractive for advertising purposes. These and other objects will be more fully described as this description progresses.

Now referring to the accompanying drawings:

Fig. 1 is a view showing an envelope in the process of being opened by the opener.

Fig. 2 is a side view of my improved letter and package opener and advertising device.

Fig. 3 is an edge view of the device shown in Fig. 2.

Fig. 4 is an opposite edge view of that shown in Fig. 3.

Fig. 5 is a top end view of the device shown in Fig. 2.

Fig. 6 is a bottom end view of the device as shown in Fig. 2.

Fig. 7 is a side view of the guide element.

Fig. 8 is an edge view of the guide element shown in Fig. 7.

Fig. 9 is an opposite edge view from that shown in Fig. 8.

Fig. 10 is a bottom end view of the guide shown in Fig. 7.

Fig. 11 is an edge view of the cutter element.

Fig. 12 is a side view of the cutter element.

Similar numerals of reference designate the same parts throughout the several figures of the drawings.

In the drawings is shown my improved envelope and package opener and advertising device as having a handle element 13 an edge view of which (see Fig. 3), gives the appearance of a

2

bottle on which advertising matter may be placed. This design would be appropriate for use in advertising beer, pop or other bottled drinks. Obviously, the handle 13 could be made to represent an automobile as an automobile advertisement, or a building for an advertisement of real estate service, etc. The handle is provided with a projecting portion 13a that is provided with a longitudinal slot 14 for purposes that will later be explained. The portion 13b represents the neck of the bottle while the portion 13c represents the cap of the bottle.

The guide is made in the form of a slender spear like element 15 which terminates in a flat sided point 16. The back edge of the blade as it progresses from point to the opposite end thereof evolves into a round rib like portion 17 which merges into a tongue element 18 that is snugly fitted into the groove 14 of the handle element 13. The guide element being so mounted in the handle element 13, the neck portion 13b of the handle will swing away from the guide blade 15 so as to leave a V shaped opening X between the guide blade 15 and the handle portion 13b of the handle 13. The edge of the guide blade 15 is provided with a slotted seat formation 19 in which is seated a cutter blade 20. The sharp edge of the cutter blade 20 is positioned diagonally across the lower portion of the V shaped opening X so that the projecting sharp point of the blade 20 is also seated in the slotted seat 19, of the guide blade 15. The several parts of the device having thus been assembled, rivets or screws 21 are passed through the projecting portion 13a of the handle 13 and the tongue element 18 of the guide 15 to rigidly bind and hold the assembly together as shown and described.

The operation of the device is as follows: To open an envelope 22, the end of the envelope may be held between the thumb and first finger of the left hand, now the handle of the envelope opener may be held in the right hand, whereupon the point 16 of the guide blade 15 may be entered under the flap 23 of the envelope 22 and the envelope opener may then be advanced along the envelope and in so doing the edge of the cutter blade 20 will engage and cut the envelope flap 23 from envelope 22 whereupon the envelope is opened.

Now to open packages wrapped with paper and tied with string the guide element may be run into the paper and advanced in any desired direction whereupon the paper will be cut in the line of travel of the opener. If strings are to be cut the guide element may be run under the string and

advanced until the cutter engages and cuts the string, thus the package may be opened.

Such modifications of my invention may be employed as lie within the scope of the appended claim without departing from the spirit and intention of the invention. Now having fully shown and described my invention, what I claim is:

In a letter and package opener device of the kind described; the combination of a one piece handle element of replica form, a guide blade and a knife, said guide blade having a tongue portion and an enlarged rib formation integrally formed on one edge thereof and merging into a long forwardly extending slender pointed blade to form the aforesaid guide blade, said handle element having a longitudinally positioned groove therein in which the tongue portion of the guide blade is seated in such a manner that a portion of the replica diverges from the guide blade to form a V-shaped opening between the replica and guide blade, said knife being in the form of a right angle triangle having an extremely long base and short altitude and the hypotenuse side of the triangle being the sharp edge of the knife, said guide blade having a groove therein in which

10

20

25

one side of the triangle knife is seated with the sharp edge of the knife extending diagonally across the apex end of the said V-shaped opening and one corner of the triangle knife engaging the replica as a means of rigidly holding the knife in place, and means passing through both the replica and said tongue to rigidly hold the replica and guide blade in their relative fixed position.

JAMES O. TILLY.
